UNITED STATES PATENT OFFICE.

PASCAL LEONE, OF NEW YORK, N. Y.

DESIGN FOR A CHARM OR SIMILAR ARTICLE.

42,485.

Specification for Design.

Patented May 7, 1912.

Application filed February 14, 1912. Serial No. 677,638. Term of patent 7 years.

To all whom it may concern:

Be it known that I, PASCAL LEONE, a subject of the King of Italy, residing at the borough of Manhattan, city, county, and State of New York, have invented a new, original, and ornamental Design for a Charm or Similar Article, of which the following is a specification, reference being had to the accompanying drawings, forming part thereof.

Figure 1 is a plan view of one side of a charm embodying my new design; and Fig. 2 is a similar view of the other side of a charm, embodying my new design.

I claim:

The ornamental design for a charm or similar article, as shown.

PASCAL LEONE.
